UNITED STATES PATENT OFFICE.

WILLIAM C. HEDGCOCK, OF CHICAGO, ILLINOIS, ASSIGNOR TO AMERICAN STEEL FOUNDRIES, OF NEW YORK, N. Y., A CORPORATION OF NEW JERSEY.

Brake.

1,223,582.

Specification of Letters Patent.

Patented Apr. 24, 1917.

Application filed March 2, 1916, Serial No. 81,598. Renewed February 19, 1917. Serial No. 149,656.

To all whom it may concern:

Be it known that I, WILLIAM C. HEDGCOCK, a citizen of the United States, residing at Chicago, in the county of Cook and 5 State of Illinois, have invented certain new and useful Improvements in Brakes, of which the following is a specification.

My invention relates to railway car brakes and has particular reference to a novel arrangement of the rigging and the support therefor.

An object in the present construction is to provide a brake rigging in which the operating levers and pull rods are duplicated on each side of the truck, the pull being applied at a point close to the brake shoes, the two sets of rigging being connected by a brake beam or brake bar, and the riggings being supported at the middle 15 through the medium of the brake beam. This construction involves the use of a novel brake beam or bar, which is specifically claimed in a co-pending application.

A further object is to provide novel means 20 for guiding the rigging and preventing lateral movement or deflection thereof. By the use of the arrangement here shown, a number of parts are eliminated, thus simplifying the rigging to a material extent.

The invention will be more readily understood by reference to the accompanying drawings, wherein—

Figure 1 is a diagrammatic perspective view of the rigging;

Fig. 2 is a sectional elevation of a portion of the rigging as applied to a car truck;

Fig. 3 is a plan view of the construction shown in Fig. 2, and

Fig. 4 is a section on the line 4—4 of 40 Fig. 2.

Referring more particularly to the drawings, it will be seen that the adaptation of the invention is to a six-wheel truck, the arrangement being of the so-called "clasp" 45 brake type. It will be seen that I provide duplicate riggings on both sides of the truck, these riggings comprising the brake levers 10, the extreme levers being anchored at 11 to a rigid portion of the truck. The 50 levers are connected by rods 12, the upper ends of the levers being connected by pairs of bars 13. The air-brake cylinder pull rod is indicated at 14. It will be noted that the two sets of riggings are located in such

position as to directly connect with the brake 55 shoes at a point contiguous thereto, and that the connection between the two sets of rigging is in the form of a brake beam or bar 15. This beam serves the double function of connecting the two sets of rigging and 60 supporting both sets of rigging from a single point. It will be noted that the beam 15 has brake heads 16 mounted on the ends thereof and that the beam is likewise provided with three sets of lugs, two at the 65 end, lettered 17, and one at the middle, lettered 18, the latter serving as the means of connection for the links 19, fulcrumed on an arm, or bracket, 20, secured to a rigid portion of the truck frame, the supporting 70 element in the present instance being the transom 21 shown in section in Fig. 2 and in elevation in Fig. 4. Referring to Fig. 2, it will be seen that the usual hangers 22 are likewise provided, these hangers connecting the brake heads with a rigid portion 75 of the frame of the truck. It will be seen that the links 19 and 22 form the sole supporting means for the two sets of rigging, thereby materially simplifying the 80 construction and eliminating a number of parts. To maintain the rigging in its proper vertical position, it will be noted that the two bars 13, which connect the upper ends of the levers 10, are engaged by 85 a bracket 23, riveted to the transom 21, as best shown in Fig. 4. This bracket merely serves to guide the bars 13 in their longitudinal movement, but does not act as a support. The wear at that point will, therefore, be but slight, and the bars will not be weakened thereby.

The advantages of the proposed construction are in that a much lighter brake beam may be employed for a given capacity, in 95 view of the fact that the force is applied at a point close to the brake heads. I am aware that this in itself is not new, but I have combined with this structure a means for supporting the rigging at a number of 100 points, and those points lie along the longitudinal center line of the truck. The parts are held in their proper vertical position by means of a suitable guide which does not act as a support, and, in general, the parts 105 are so combined and associated that extreme simplicity results therefrom. This in a clasp brake for six-wheel trucks is very

desirable in view of the large number of parts which have heretofore been considered necessary in an arrangement of that sort.

I claim:

5. 1. In a brake, the combination of levers and pull rods, one complete set of which is located at each side of a truck, a beam or bar connecting the two sets of riggings and a support for said rigging located intermediate the length of said bar.
10. 2. In a brake, the combination of brake levers and connecting rods, one complete set of which is located at each side of a truck, whereby said levers are connected and apply their force at a point close to the brake shoes, beams or bars connecting the riggings on opposite sides on the truck, and supporting elements connected to said beams at a point intermediate their ends and located substantially at the longitudinal center line of the truck, substantially as described.
15. 3. In a clasp brake for trucks, the combination of brake shoes applied to each side of each pair of wheels, a beam connecting each pair of shoes, brake levers, one at each end of each beam, connections between the brake levers of each side of the truck, a cylinder pull rod for each set of levers, and supporting links connected to said beams, said supporting links comprising the sole supporting means for said rigging.
20. 4. In a brake, the combination of brake levers and connecting rods, the rods connecting certain of said levers providing a
- space therebetween, and a bracket connected to a rigid part of the truck and projecting into said space, whereby said rigging is guided against lateral movement, substantially as described. 40
5. In a brake arrangement, the combination of heads carrying shoes, a brake bar connecting adjacent heads, a brake rigging located at each side of the truck and connected to said brake bars at a point close to said head, and supporting means for said riggings and bars applied directly to said bars at a point substantially on the longitudinal center line of the truck, substantially as described. 45
6. In a brake, the combination of brake heads and shoes applied to both sides of each pair of wheels, a brake bar connecting said heads, and a brake rigging at each side of said truck, the brake levers of which rigging are connected to said brake bars at a point close to said brake heads, the brake levers at an extreme end of the truck, being anchored to the truck, whereby the pull is from the opposite end of the truck, guiding means applied to said riggings and supporting means applied to said brake bars, substantially as described. 50
55. Signed at Chicago, Illinois, this 28th day of February, A. D. 1916.

WILLIAM C. HEDGCOCK.
